INSULATOR

Filed July 29, 1919

Fig. 3.

UNITED STATES PATENT OFFICE.

MINOR F. H. GOVERNEUR, OF ROCHESTER, NEW YORK, ASSIGNOR, BY MESNE ASSIGNMENTS, TO LOCKE INSULATOR CORPORATION, OF BALTIMORE, MARYLAND, A CORPORATION OF MARYLAND.

INSULATOR.

Application filed July 29, 1919. Serial No. 313,974.

My invention relates to insulators for use with transmission lines for high voltage currents and more particularly to suspension insulators, and its primary object is to provide a simple, strong, reliable and efficient means for connecting the hardware to the porcelain body portion of a suspension insulator unit.

To this end the main feature of my invention, broadly stated, consists in employing a connected series of units as the connecting means between the porcelain body portion and the cap and eyebolt, or the hardware as they are called, of an insulator, and in so modifying the porcelain and hardware as to adapt the same to receive the said units and to maintain the latter in such position as will enable the units to withstand the greatest strain without deformation.

Another object of my invention is to provide the porcelain body portion of a suspension insulator with an undercut circumferential groove and to provide a like groove in the adjacent metallic connecting member and to interpose a spring ring between the shoulders formed by the said grooves, said ring being introduced into position by moving said ring relatively to one of said shoulders.

Another object of my invention is to provide a device for connecting the hardware to the porcelain of a suspension insulator, said device permitting the ready assembly of the parts of the suspension unit and automatically locking said parts and preventing their disengagement when assembled.

Still another object of my invention is to provide mechanical means for interlockingly connecting the parts of suspension insulator units, said means being adapted to maintain the parts in engagement under all conditions and to eliminate the stresses and strains on the porcelain which have been incident to the use of cement as the connecting medium between the porcelain and the hardware.

There are other objects of the invention as will more fully appear from the detailed description of the single embodiment of the invention which has been chosen to illustrate the same and in which:

Figure 1 is a transverse vertical section

of a suspension insulator unit, showing the invention applied thereto;

Figure 2 is a side elevation of a portion 55 of an eye-bolt for insulators showing the spring ring connecting means applied thereto and in normal position;

Figure 3 is a fragmentary view showing the manner of introducing the eyebolt and 60 connecting means within the insulator body;

Figure 4 is a top plan view of the spring ring adapted for use with the eyebolt; and

Figures 5 and 6 are fragmentary views 65 showing one method of connecting the metallic cap and associated spring ring to the neck of the porcelain body portion of the insulator unit.

Throughout the specification and drawings, like parts are designated by like reference characters.

Referring now to the drawings, the insulator 1 preferably comprises a porcelain body portion 2 having a skirt portion 3 and a neck or stem 4. Adjacent the juncture of the neck and skirt portions the former is provided with an undercut circumferential groove 5, which may be and preferably is provided with a curved or rounded upper end 6. Within the neck 4 and opening from the underside of the insulator is a bolt receiving socket or bore 7, which may be and preferably is provided adjacent the closed end with an undercut outwardly flaring circumferential recess 8.

The cap 9 is preferably provided with an outwardly flaring ring or band 10 adjacent the lower edge thereof said ring being provided on its inner face or surface with a groove or recess 11. The eye-bolt 12 is provided with a stem 13 and adjacent one end thereof is provided with an outwardly flaring head or cap 14 which is preferably of a diameter substantially equal to that of the bore or recess 7, which is provided in the underside of the porcelain body portion 2. Intermediate the cap 14 and the eye 15 the bolt is provided with a ring or collar 16 which will be hereinafter more fully described.

To connect the parts of the insulator unit I employ spring rings 17 and 17^a. These rings are made from tempered steel, the wire, rod or bar being preferably of rectangular

section, as shown. The wire is wound to form a series of substantially elliptically shaped coils 18, that is, each coil has a long and a short axis, the sides of each coil being preferably substantially parallel, as shown at 19. In winding the spring the coils are arranged at an angle to each other, so that when the ends of the spring are welded together, or otherwise suitably connected, the spring ring so formed comprises a plurality of separate coils, the upper ends of which are in close engagement while the lower ends are spaced apart, as clearly shown in Figure 4. The spring rings 17 and 17^a are arranged so that in normal position the upper portions thereof just fit with but slight expansion, the adjacent portions of the eyebolt and the insulator stem respectively.

To assemble the eyebolt with the insulator 20 the ring 17 is slipped over the head of the eyebolt, the coils opening at the top sufficiently to permit the passage of the said head. The spring ring 17 now occupies a position, such as illustrated in Figure 2, the 25 upper ends of the coils tightly fitting the eye-bolt below the head and the spring ring flaring outwardly from the said head. The bolt and associated spring ring are then entered within the opening 7 of the body portion 30 of the insulator, the engagement of the side of the opening forcing the spring to assume a position parallel to the axis of the eyebolt, as clearly shown in Fig. 3, the spring being maintained in position on the bolt by 35 means of the collar 16, hereinbefore referred to. In order to assume a position parallel to the axis of the eye-bolt, the coils at the lower end of the spring ring must approach and the coils at the upper end separate. It 40 will be therefore obvious that as soon as the eyebolt has entered the enlarged recess 8 sufficiently to permit the lower edge of the spring ring 17 to pass the shoulders at the lower end of the undercut enlargement, the 45 spring will be free to expand and to assume its normal position, shown clearly in Figures 1 and 2, thereby automatically locking the eye-bolt to the porcelain.

The method of connecting the cap to the insulator is very similar to that just described. In the form of construction shown in Figure 1 the ring 17^a is slipped over the stem and forced downwardly until the upper end of the ring seats in the groove 6. The 50 cap is then forced over the spring ring, the ring being received within the groove 5 until the lower edge of the cap passes the lower edge of the ring and thus allows the spring to assume its normal position with its lower 55 end in engagement with the groove or recess 11 in the cap 9, thus automatically locking the cap to the insulator body. With the form of cap shown in Figures 5 and 6, the 60 stem 4^a of the insulator is provided with an 65 undercut groove 6^a, the inner wall of said

groove instead of being substantially vertical, as shown in Figure 1, being inclined outwardly, forming in effect a fillet between the stem 4^a and the skirt portion of the insulator. The cap 9^a is provided with a spring ring receiving groove 21 and the spring ring 17^a is inserted within this groove 21 and is forced down over the stem 4^a until the upper end of the ring 17 is in alignment with the groove 6^a, when the contraction of the spring ring forces the upper portion of the ring into locked position within this groove. To prevent oxidation of the spring rings 17 and 17^a I preferably fill the cavity 7 and the space between the cap and neck of the insulator 75 with some elastic compound, such as sarco, one of the coal tar derivatives possessing great elasticity which is indicated on the drawing by the reference character 20.

It is believed it will lead to a better understanding of the great importance of the invention if a brief reference is made to the defects of the usual type of suspension insulators before pointing out the advantages of 80 this novel form of construction.

It is common practice to use cement as a medium for connecting the cap and eyebolt to the porcelain of an insulator, but cement has not proved satisfactory for several reasons, among which may be named the following: First, cement constantly increases in 85 volume during the life of the insulator and this increase causes terrific pressure to be brought on the porcelain. This pressure is often so great as to cause the breaking of the 90 insulator. Second: Owing to the fact that cement is inelastic it has been found impossible to compensate, in an insulator, for the 95 expansion and contraction of the metallic element.

The above-named, are believed to be, the 100 primary causes of the failure of cement connected suspension insulators, since the stresses and strains, produced by the cement bond, as above outlined, would reduce the 105 electrical resistance of the porcelain and would 110 explain the failure of such insulators in cases where break-downs have occurred and where the failure could not be explained by the amount of the overload, both electrical and mechanical, known to have been impressed upon the insulator.

By my improved form of connecting means the stresses on the insulator due to the 115 expansion of the cement and to the expansion of the metallic parts under atmospheric 120 conditions are avoided. It is obvious from a consideration of Figure 1 that should the 125 eyebolt expand no tension will be placed upon the porcelain, since the result of this expansion will be merely to slightly enlarge the upper diameter of the spring ring. Likewise, the expansion or contraction of the cap will merely result in the spreading or contracting of the lower diameter of the spring 130

ring without causing tension or stress on the porcelain body portion. It will therefore be obvious that by my improved form of construction the porcelain is entirely relieved 5 from the destructive effects of the expansion and contraction and I have at the same time provided a strong and reliable means for connecting the porcelain to the hardware. It will be seen that the lines of stresses are 10 practically parallel to the long axes of the spring coils and therefore the spring coils resist with their maximum strength all tendencies of the hardware to move relatively to the porcelain. In addition to the advantages above set forth attention is directed to 15 the fact that by the use of a spring ring I obtain adequate bearing on the porcelain since the ring being flexible is enabled to accommodate itself to all inequalities of the 20 porcelain and therefore evenly distributing the load over the entire field.

Having now described my invention what I claim and desire to secure by Letters Patent is:—

25 1. A locking device for connecting insulator elements, said device comprising a spring

ring adapted to be interposed between the insulator elements and having coils formed with non-circular openings.

2. A locking device for connecting insulator elements, said device comprising a spring ring of normally conical form composed of a series of connected coils having their faces lying in the same plane, said coils being adapted to be interposed between the said 35 insulator elements.

3. A locking device for connecting insulator elements, said device comprising a series of normally divergent connected coils which are adapted to be interposed between the in- 40 sulator elements.

4. A locking device for connecting insulator elements, said device comprising a series of coils formed with elongated openings extending in the direction of length thereof, 45 the ends of said coils being adapted to be interposed between said insulator elements and the sides of said coils being disposed substantially in the lines of strain communicated to them by said insulator elements. 50

In testimony whereof I affix my signature.
MINOR F. H. GOUVERNEUR.
